UNITED STATES PATENT OFFICE.

FERDINAND W. HUEMPFNER, OF CHICAGO, ILLINOIS, ASSIGNOR OF ONE-THIRD TO
MID-STATES GUMMED PAPER COMPANY, OF CHICAGO, ILLINOIS, A CORPORATION
OF ILLINOIS, AND ONE-THIRD TO GEORGE F. SCHILLING, OF CHICAGO, ILLINOIS.

PRINTING PRESS.

Application filed November 25, 1922. Serial No. 603,304.

To all whom it may concern:

Be it known that I, FERDINAND W. HUEMPFNER, a citizen of the United States, residing at Chicago, in the county of Cook and State of Illinois, have invented certain new and useful Improvements in Printing Presses; and I do hereby declare the following to be a full, clear, and exact description of the invention, such as will enable others skilled in the art to which it appertains to make and use the same.

This invention relates to an improvement in printing presses, and is particularly concerned with the provision of improved means for supplying different colored inks to the type form of the press.

Generally stated, it is the object of the invention to utilize the axial reciprocations of a "vibrator" roller not only to evenly distribute inks of different colors over the roller or rollers posterior to it with respect to the flow of ink through the press, but also to utilize such reciprocations for applying the inks to the said posterior roller or rollers in such fashion that spaces between adjacent colors are minimized or practically eliminated without danger of the colors becoming mixed.

The invention also contemplates a novel roller construction hereinafter described in detail. This improved construction is preferably incorporated in the vibrator, but is not necessarily limited to such use. Other features, objects and advantages will hereinafter appear.

In the accompanying drawings illustrating the invention:

Figure 1 is a vertical section passing transversely through the inking rollers of a bed and platen printing press and indicating diagrammatically the inking mechanism, form, platen and paper.

Figure 2 is a diagrammatic development of the several inking rollers, the form and the printed stock, all arranged to illustrate most clearly the method by which the several colored inks from a divided fountain are brought closely together on the printed stock.

Figure 3 is a side elevation of the vibrator roller of this invention, illustrating the sleeve sections all brought together to form a plain surface vibrator.

Figure 4 is a view similar to Figure 3, but

showing the sleeve sections rearranged with gaps between certain of the sections, and a smaller split section inserted to compensate for the gaps, this being the arrangement of the sectional vibrator for the "set-up" illustrated in Figure 2.

Figure 5 is an enlarged longitudinal section of the vibrator, as shown in Figure 4.

Figure 6 is a transverse section of the vibrator taken on the line 6—6 of Figure 4.

Figure 7 is a view which may be considered as a partial continuation of Figure 5, and which shows the relation of the split sleeve section to adjacent sleeves.

Figure 8 is a side elevation of an improved divider as applied to the fountain roller for the purpose of separating inks of different colors.

Figure 9 is a top plan view of the divider, as illustrated in Figure 8.

Figure 10 is a vertical section taken on the line 10—10 of Figure 9.

Figure 11 is a sectional view on the line 11—11 of Figure 9.

Throughout the several views similar characters of reference will refer to similar parts.

I have chosen to illustrate my invention as applied to a bed and platen press, and, for the sake of clarity, I have included in the drawings only those elements of the press to which it will be necessary to refer, and have indicated these elements for the most part diagrammatically.

Referring to Figures 1 and 2, from the ink fountain 10 the ink 11 is fed onto the steel fountain roller 12, the amount of feed being regulated in the usual manner. The fountain roller 12 is given a slow intermittent rotation through the ratchet 14. Between the fountain roller 12 and the steel idling roller 15, reciprocates the ink transmitting or "duck" composition roller 16, which is swung arcuately about a stationary pivot 17 by means of an eccentric 18 in one arm of the bell crank 19. From the steel roller 15 the ink travels onto the idling composition roller 20 which is anterior to and contacts the steel vibrating roller 21, to which rotation is imparted through an end gear 22 (Figure 3). Posterior to the vibrator 21 is a pair of "angle" rollers or idling composition rollers 23, which contact both the vibrator 21 and the large ink-

ing cylinder or roller 24. The ink is taken from the inking cylinder 24 by a pair of form rollers 25 which travel downwardly along the track 26, where they ink the vertically disposed type form 27 within the chase 28, which in turn is held in the bed 29.

For the purposes of this specification there is described as an example of the work to be done, the printing upon a continuous roll of gummed paper certain trademarks, names and the like in such manner that the stock may be cut into strips and rewound for commercial use with gummed tape dispensers for sealing packages. Referring again to the drawings, the gummed stock 30 is fed from the supply roll 31 across the platen 32 and thence (Fig. 2) under the shaft 33 carrying knives by which the paper is cut into a plurality of narrow tapes 34. It is to be understood, of course, that the platen 32, following the inking of the form by the form rollers 25, is swung upwardly about its pivot 35 by the usual means (not shown) to print a length of paper, following which another length of paper is fed across the platen.

Referring now to the construction of the vibrator of my invention (Figures 3 to 7, inclusive), it will be seen that, while the external conformation of the roller is substantially that of the vibrating rollers commercially in use, the vibrator roller here illustrated is not turned from a solid shaft, but is composed of a shaft 36 constituting a core having at its ends reduced portions 37 slidably journaled within the bearings 38. The extreme ends of the core 36 are provided respectively with the gear 22, and with a spool 39. The roller is vibrated by the vibrating mechanism 40 acting through the spool. A plurality of sleeve sections 41 are slipped onto the core 36, one end of each sleeve being shouldered as at 42, while the opposite end of each sleeve is provided with a counter bore 43 for the reception of the shouldered portion 42 of an adjacent sleeve in such a manner that, when adjacent sleeves are pushed together, they join, leaving only an annular hair line upon the outer surface of the roller. Each sleeve section is provided with a key-way 44, whereby the sleeves are feathered upon a key 45 of the core 36. Each sleeve may be selectively clamped longitudinally on the core 36 by means of a small set screw 46 in the reduced portion 42.

It will be seen that because the vibrator sections 41 may be made to fit closely together, the roller, when assembled as in Figure 3, will, to all intents and purposes, serve as well as the usual solid vibrator roller where the printing is done in one color, or where the fountain is divided and the ink is fed by the methods heretofore commonly employed.

When the press is to be adapted for work wherein different colors are to be printed simultaneously, such as the blue, black, green and orange indicated in Figure 2, the vibrator roller is divided into four corresponding portions which are separated by gaps 47 (Figure 4). This is accomplished by loosening the set screws 46, the sleeve sections being slipped longitudinally of the core shaft 36 and grouped together in their proper positions. To facilitate the ready sliding of these sleeves 41 and to eliminate the necessity of removing the roller to slip shorter sections onto the core to compensate for the width of the several gaps 47, I make one of the sleeves in two parts, as indicated at 48. As shown in Figure 7, the split sleeve is shouldered at both ends, forming reduced portions 42'. The full sections on one side of this split sleeve are reversed from those on the other side, so that the ends of the two adjacent full sections having the counter bores 43 slip over the reduced portions 42' and hold the two halves of the split ring firmly together. No set screws need be provided on the split ring.

To reposition the sleeves, the full sleeves at one side of the split ring are slid longitudinally sufficiently to allow the counter bores to disengage the shoulders of the split ring and allow the ready removal of the latter. The several sleeves are then positioned as shown in Figure 4, and so retained by tightening their set screws. The original split ring cannot be replaced because the introduction of the gaps 47 no longer leaves sufficient room, but a shorter split ring indicated at 48' is inserted and held in the same manner as the longer split section. In practical use it is not necessary that each set screw be tightened, but only the terminal set screws in the sections between which there is no gap. I contemplate that several split rings of different length be provided from which the operator may select the length most suitable for the required spacing of the sections. It is obvious also that shorter lengths of sections may easily be employed, and that the shorter the sections are, the more accurately the roller may be divided for each color of ink.

The division of the vibrating roller as shown in Figure 4, is indicated in Figure 2, but for the sake of clearness, the length of the roller has been proportionately foreshortened, and only the gaps 47 indicated, the lines indicating abutting sections being omitted. The ink fountain has been divided with the ink dividers 49, and the spaced colors of ink are fed onto the composition roller 20, which lies anterior to the vibrator. The space between adjacent inks is thus the width of the separator 49.

When the right-hand edge 50 of the gap on the vibrator between the blue and the black ink moves from its dotted line position, where the edge 50 has been well fed with black ink from the composition roller 20, to the full line position, the angle rollers 23 are fed with black ink up to the line 51. At the full line position of the roller, the opposite or left-hand edge 50' of the gap is well supplied with blue ink, and conversely, when the vibrator reciprocates to its dotted line position, the edge 50' will lead the blue ink up to the line 51 and a space of $\frac{1}{2}$ of an inch—or less, if necessary—from the black ink. Similarly, the black and green inks and the green and orange inks are brought to hair line contacts by the vibrator. Having been delivered by the vibrator to the composition rollers 23 posterior to the vibrator, the ink is fed in this same hair line spaced relation onto the inking cylinder 24, the form rollers 25 and the form 27, from which it is transferred to the paper in a well-known manner.

Where the nature of the printing to be done is such that the green printing, for instance, extends to the margin of a strip 52 and the orange printing extends to the margin of an adjacent strip 53, it is necessary that the green and the orange inks be brought onto the type form with substantially no space between them. In those cases where the nature of the printing is such that 1.8 of an inch or so may be left between the two colors, the corresponding gap 47 in the vibrating roller may be made a little wider in order to prevent danger of any overlapping of colors due to inaccurate adjustments or to slight side play in any of the rollers.

Figures 8 to 11 inclusive illustrate an embodiment of an improved ink divider adapted to be applied to the printing press, as used in accordance with this invention. The same comprises a partition 49 having a semi-circular face adapted to correspond with the face of the fountain roller 12. An integral projection 62 is also provided on the partition 49, and is adapted to extend around the edge of the ink fountain 10 to which the device is clamped by means of a screw-threaded member 61. In order that the partition may closely cooperate with and fit tightly against the ink fountain roller 12, the end of the same is comprised of a plurality of members having their faces formed in a semi-circle, as illustrated, each of which is faced with a lining of cork 72, or other similar or slightly compressible material. Projections 73 are provided in the faces to prevent slippage of the lining 72.

Portions of this cork lining are mounted on the two ends of a U-shaped block 63, forming part of the main partition mem-

ber 49, and another portion of the lining is placed upon an adjustable block 68 slidably mounted within the two arms of the U-shaped block 63.

Proper adjustment of the slidable block 70 member 68 is obtained by means of screw-threaded members 64, rotatably fitted into the U-shaped block 63, each having one end extending outwardly beyond the edge of the ink fountain 10, and provided with a head 75 in the shape of a winged nut. These bolts 64 are rotatably fitted in the body of the block member 68, and are fixed therein by means of nuts or the like 66, as best illustrated in Figure 10. The lining or facing 80 on the adjustable block 68 is designated by the reference numeral 69, and extends slightly above the linings 72 on the fixed members.

Pivotedly mounted on the main partition 85 member 49 is a lever 70, having its upper end free and adapted to be acted on by the end of an adjusting screw 71, similar to the screws 64. The lower end of the lever 70 is adapted to cooperate with a block 75 extending longitudinally along the outer edge of the ink fountain 10, and fixed thereto by means of screws or the like 76. It will be apparent that tightening the screw 71 will act through the lever 70 to force the partition 49 forwardly against the roller 12. In this manner a triple adjustment is secured which positively prevents any mixing of the different inks.

The resilient facing of cork or the like, as shown at 69 and 72, are therefore adapted to be adjustably fitted against the ink distributing roller 12, and the double or U-shaped construction of the main lining support 63 positively prevents any mixing 103 of the inks, as even should some slight portion of the ink flow between the face of one of the linings 62 and the ink roller, it would not be immediately mixed with ink from the other side, which might flow through, 110 but would necessarily be detained by the adjustable retaining means 69. The triple lining herein illustrated absolutely prevents any possibility of mixing of the different colored inks, and constitutes one of the important improvements in this apparatus.

As previously stated, one of the features of my invention is that it may be adapted to a printing press already in use without the addition, alteration or modification of 120 any of the parts save the vibrating roller. I have found, however, that in practice, after printing machines have been run for sometime, some slight longitudinal play develops in the rollers, and it is sometimes 125 advisable in work where hair line contact between the colors will be required to overcome this end play, especially in the rollers posterior to the vibrator, by a resetting of the bearings or the introduction of thin 130

washers. The sectional vibrating roller may easily be cleansed and the sleeve sections quickly reset for other work, without the necessity of removing the roller from the frame of the machine.

It will be readily perceived by those skilled in the designing of printing presses that the principles of this invention are by no means confined in their application to

10 a printing press of the type which has been selected for the purposes of this specification, but that it is readily adaptable to either one or two color presses, to rotary cylinder presses, and that it makes no inherent 15 difference in the application of my invention whether the ink is delivered from the vibrating roller to the printing type through the agency only of rollers, or of an inking plate, or of other suitable means.

20 Many departures could be made from the specific constructions, and arrangements here shown without departing from the spirit and scope of my invention.

What I claim is:

25 1. In combination with a printing press, means for feeding different inks from a single fountain comprising a divider adapted to be applied to said fountain, said divider including a member adapted to be 30 removably applied to said fountain, clamping means to maintain said member in position on the fountain, and adjustable ink retaining means on said member adapted to cooperate with the inking roller of the printing 35 press, said means including a relatively movable member adapted to fit closely against the ink roller, means for adjusting the position of said relatively movable member, said means including thumb screws mounted in the divider member.

40 2. In combination with a printing press, means for feeding different inks from a single fountain comprising a divider adapted to be applied to said fountain, said divider 45 including a member adapted to be removably applied to said fountain, clamping means to maintain said member in position on the fountain, and adjustable ink retaining means on said member adapted to cooperate with

the inking roller of the printing press, said 50 means including a relatively movable member adapted to fit closely against the ink roller, means for adjusting the position of said relatively movable member, said means including thumb screws mounted in the 55 divider member, and a lever on the divider for relatively adjusting the relation of same to the fountain roller.

3. In combination with a printing press, means for feeding different inks from a 60 single fountain comprising a divider adapted to be applied to said fountain, said divider including a member adapted to be removably applied to said fountain, clamping 65 means to maintain said member in position on the fountain, and adjustable ink retaining means on said member adapted to cooperate with the inking roller of the printing press, and a lever on the divider for relatively adjusting the relation 70 of same to the fountain roller.

4. In combination with a printing press, means for feeding different inks from a single fountain comprising a divider including a U-shape member adapted to be 75 removably applied to said fountain, an adjustable ink retaining means suitably positioned between the arms of said U-shape member adapted to cooperate with the inking roller of the printing press, and means 80 for adjusting said ink retaining means independently of said U-shape member consisting of a multiplicity of set screws.

5. In combination with a printing press, means for feeding different inks from a 85 single fountain comprising a divider adapted to be applied to said fountain, said divider including a U-shaped member adapted to be removably applied to said fountain, an adjustable ink retaining means 90 suitably positioned between the arms of said U-shape member adapted to cooperate with the inking roller of the printing press, and means for simultaneously adjusting said ink retaining means and said U-shaped member 95 with respect to said inking roller.

In testimony I affix my signature.

FERDINAND W. HUEMPFNER.
